US00D838830S

(12) **United States Design Patent** (10) **Patent No.:** **US D838,830 S**
Puffer et al. (45) **Date of Patent:** **** Jan. 22, 2019**

(54) **VENT HOOD**

(71) Applicant: **Broan-NuTone, LLC**, Hartford, WI (US)

(72) Inventors: **Benjamin Thorpe Puffer**, Hartford, WI (US); **Jeremy Donald O'Halloran**, Pittsburgh, PA (US)

(73) Assignee: **Broan-NuTone LLC**, Hartford, WI (US)

(**) Term: **15 Years**

(21) Appl. No.: **29/636,559**

(22) Filed: **Feb. 9, 2018**

Related U.S. Application Data

(60) Division of application No. 29/565,433, filed on May 20, 2016, now abandoned, which is a continuation-in-part of application No. 29/527,426, filed on May 19, 2015, now Pat. No. Des. 814,009.

(57)

CLAIM

The ornamental design for a vent hood, as shown and described.

DESCRIPTION

FIG. 1 is an Upper Perspective View of a first embodiment of the invention.

FIG. 2 is a Lower Perspective View of a first embodiment of the invention.

FIG. 3 is a Top Planar View of a first embodiment of the invention.

FIG. 4 is a Bottom Planar View of a first embodiment of the invention.

FIG. 5 is a Front Planar View of a first embodiment of the invention.

FIG. 6 is a Back Planar View of a first embodiment of the invention.

FIG. 7 is a Left Side Planar View of a first embodiment of the invention; and,

FIG. 8 is a Right Side Planar View of a first embodiment of the invention.

Portions shown in broken lines are for environmental purposes but do not constitute a part of the claimed invention.

1 Claim, 6 Drawing Sheets
